UNITED STATES PATENT OFFICE.

PAUL H. LACEY, OF CHICAGO, ILLINOIS.

IN-CORNER RETAINER STRIP.

Application filed April 18, 1927. Serial No. 184,485.

This invention relates to incorner retainer strips, and its principal object is to provide a strip of novel form for use in connection with the incorners of base board construction, the incorner of plastered walls and other situations where a strip of this type is usable.

It is common to provide a race way behind the base boards of rooms for containing electric wires, cables and the like, and much inconvenience and annoyance is encountered in holding the wires in place at the incorners of the room before the base boards have been put in place. The wires have a tendency to fall forward out of the race way at the incorners and often it requires much time and patience for the workmen to hold the wires in place at an incorner and put the base boards in place at the same time. Usually base boards must be mitred at the corners of the room, which takes time and great skill to make a neat and finished job. Plasterers find great difficulty in making neat jobs of the incorners of the room. With the use of the incorner retainer strip, forming the subject matter of this specification, the difficulties usually present in the situations mentioned, as well as in other situations are entirely eliminated, and the usual difficult tasks mentioned are made simple and less time and skill is required than heretofore to obtain the most efficient results.

The invention consists in an incorner retainer strip, having side webs or flanges adapted to be nailed, screwed or otherwise secured to walls or other supports and having means for retaining an unwieldy article or object in place, and affording a finishing edge for the wall or trim at an incorner. The invention further consists in the several novel features hereinafter fully set forth and claimed.

The invention is clearly illustrated in the accompanying drawing, in which:

Fig. 1 is a perspective view of the incorner retainer strip, showing its application to an incorner of a room at and adjacent the base board construction; Fig. 2 is a perspective view similar to Fig. 1 but showing the base boards removed and Fig. 3 is a detail horizontal section through the base board construction seen in Figs. 1 and 2.

Referring to said drawing, which illustrates a simple embodiment of the invention, the reference characters 5, 5 designate frag-

ments of two walls of a room which form an incorner thereof, and 6 designates a fragment of the floor at said incorner. In constructions where a race way 7 is employed for containing electric wires, cables or the like 8, spaced upper and lower ground strips 9, 10, are employed, which are nailed or otherwise secured to the walls 5 to provide the space between them for the race way 7. The walls are usually plastered above the upper ground strips as at 12. In certain base board constructions a grooved shoe 13 is used in front of each lower ground strip, and the base boards 14 extend from said shoes to the plaster and cover the open fronts of the race ways. In situations where grooved shoes are used the base boards are formed with tongues on their lower edges that enter the grooves of the shoes. The base boards are secured to the upper ground strips by screws or nails 15 as usual. It will be observed that without the use of an incorner retainer strip at the incorner, the electric wires are very likely to fall forward at the incorner when the base boards are not in place, which makes it exceedingly difficult to put the base boards in place without doing serious injury to the insulation of the electric wires.

To overcome this difficulty I provide an incorner retainer strip 16 at said corner and secure it to the upper and lower ground strips by screws, nails or the like 17, thereby providing a retaining member in front of the race way at the incorner, which effectively holds the wires in the race way at the corner and prevents them from falling forward.

As shown the incorner retainer strip is formed of thin material such as metal, fibre or other composition, and contains two side webs or flanges 18 usually extending at right angles to each other and provided with screw holes through which the screws 17 are inserted. From the side webs or flanges 18 extend end webs or flanges 19, which stand at right angles to the side webs or flanges 18 and project into the angle formed by two side webs or flanges 18. The end webs or flanges 19 usually form a right angle and join with each other at the corner 20, and as a preference said corner 20 is in the form of a narrow bead or rib although not necessarily so, but the beaded form gives a more attractive finish to the strip and provides an overhanging edge portion for temporarily retaining the base boards in place before

they are screwed or nailed to the upper ground strips. The ends of the base boards are cut square and placed against the end webs 19, with the beaded corner 20 overhanging the ends of the base boards. If desired, the upper end of the incorner retainer strip may be given a finished appearance by supplying it with an ornamental top member 21 secured to the strip in any desirable manner.

It will be observed that with base boards removed, the electric wires may be laid in the race way and passed behind the incorner retainer strips where they will be effectively held from falling forward out of the race way and for this reason they do not interfere with the work of putting the base boards in place and fastening them to the ground strips. Furthermore because of the beaded corner portion 20 of the incorner retainer strip it is unnecessary to mitre the ends of the base boards at the incorner ends thereof, but a very attractive and finished appearance is given to said base boards at the incorner by the beaded edge of the incorner retainer strip.

The incorner retainer strip may also be used with great advantage at the incorners of the plastered walls above the base portion as is clearly shown in Fig. 1, as the end webs or flanges 19 of the strips serve as guides for the plasterers in plastering the walls 5 at the incornered portion. When used in connection with the plastered walls the side webs or flanges of the incorner retainer strips are secured to the main walls by nails or otherwise. It will be observed that with the present incorner retainer strip, the usual difficult task of forming a neat incorner is made simple and does not require the high grade of skill usually required of workmen in doing a neat job at the incorners of rooms.

While I have shown the invention applied to the base board construction and plastered walls of the incorners of rooms it is to be understood that the device is useful

in many other situations and for this reason I do not desire to limit myself to such uses for the incorner retainer strip.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. An incorner retainer strip having two angularly disposed side webs adapted to be secured to ground strips of a base board construction at the incorner of a room and having end webs bent up therefrom and extending entirely at right angles to the side webs and entering the angle formed thereby, the adjacent edges of said end webs being united by a bead like corner, each side web, end web and the bead like corner forming a groove of a width equal to the thickness of a base board and adapted to receive the end thereof.

2. As a new article of manufacture, an incorner retainer strip formed with angularly disposed side webs adapted to be secured to the upper and lower ground strips of base board constructions and having bent up end webs extending entirely at right angles to the side webs and entering the angle formed by said side webs, said end webs being of the same width as the thickness of the base boards and united by a bead like corner portion adapted to overhang the ends of base boards secured on said ground strips.

3. The combination with angularly disposed upper and lower ground strips and removable base boards forming therewith a race way, of incorner retainer strips secured to said ground strips at the incorner formed thereby and adapted to retain flexible members in said race way at the incorner thereof.

PAUL H. LACEY.
